PERMUTATION PIN TUMBLER LOCK

John F. Ching, Berkeley, Calif.

Application November 21, 1939, Serial No. 305,489

4 Claims. (Cl. 70—382)

This invention relates to key-operated locks and particularly to the species thereof commonly known as pin tumbler locks.

It is an object of the invention to provide a lock of the class described whose combination may be readily changed without disassembling the lock.

Another object of the invention is to provide a lock of the pin tumbler variety in which at least one set of tumblers may be displaced relative to the positions of other sets of tumblers so as to change the combination of the lock.

A further object of the invention is to provide a lock of the class described whose combination may easily be changed by a person not possessing a great deal of mechanical skill.

The invention possesses other objects and features of advantage, some of which, together with the foregoing, will be specifically set forth in the detailed description of the invention hereunto annexed. It is to be understood that the invention is not to be limited to the specific form thereof herein shown and described as various other embodiments thereof may be employed within the scope of the appended claims.

Referring to the drawing:

Figure 1 is a vertical sectional view taken longitudinally through a lock, of the rotary-barrel pin-tumbler type, showing the improvements of my invention incorporated therein.

Figure 2 is a vertical sectional view of the lock. The plane in which the view is taken is indicated by the line 2—2 of Figure 1.

Figure 3 is a vertical sectional view of the lock. The plane in which the view is taken is indicated by the line 3—3 of Figure 1.

The common familiar pin-tumbler lock comprises a unitary barrel provided with a longitudinal bore in which the key-receiving lock rotor is rotatably journaled. The rotor is provided with a plurality, usually five, of longitudinally spaced radial bores in which are slidably mounted short sections of round rods forming halves of the lock tumblers. Similar short rods are slidably mounted in bores in the barrel which are similarly spaced with, and adapted to be brought into axial registry with the bores of the rotor as the latter is rotated. Springs are usually provided in each bore so as to maintain the two rod sections of each tumbler in abutting relation. The key provided for operating such a lock has usually five notches of various depths cut into one edge thereof so that upon insertion of the key in the keyway provided therefor in the lock rotor, each tumbler will be moved to

assume a position in its bore which is slightly different from that of its neighbor and the depths of the key notches and lengths of the lower sections of the tumblers are made so that the plane of division of each tumbler will be brought to coincide with the periphery of the rotor. The rotor is thus free to be rotated, carrying with it the lower section of each tumbler. When the rotor is brought back to normal position, wherein the tumbler bores of the barrel and rotor are in alinement, and the key is withdrawn from the rotor, the upper sections of the tumblers will fall or be spring pressed partly into the bores of the rotor thus pinning the rotor and the barrel together so that the rotor may not be thereafter rotated unless the proper key is used to unlock it.

Frequently a key is lost and in order to preclude unauthorized opening of the lock by anyone who happens to find the key, it is necessary to change the combination thereof. This usually requires the services of a skilled locksmith who dismantles the lock, makes a new key, in which the depth of one or more of the tumbler notches is altered, places the new key in the rotor, fits the lower section of each tumbler so that it will terminate flush with the periphery of the rotor, and then reassembles the lock. It will be seen that work of this nature is beyond the skill of the ordinary person, consumes considerable time and is consequently quite costly. I have provided a lock structure which permits the lock combination to be repeatedly changed as desired without the necessity of taking the lock apart or altering the tumblers and which permits this adjustment to be done by a person possessing no great mechanical skill.

Describing my invention in detail, I provide a tubular sleeve 4 having adjacent an end thereof external screw threads 6, and being provided in the interior thereof with a bore 7, internal screw threads 8, and a counterbore 9. The end of the bore 7 is provided with an inwardly directed flange 11. Journaled in the counterbore 9, for rotation with respect to the sleeve 4, is a cylindrical lock barrel 12 having an end flange 13 which abuts against the end of the sleeve 4 so as to prevent relative axial displacement between the barrel and the sleeve in one direction. The lock barrel is provided with a peripheral groove 14, and setscrews 16 tapped radially through the wall of the sleeve have their ends seated in, and frictionally engaging the bottom of, the groove so that, when the setscrews are loosened, the sleeve and barrel may be relatively

rotated, the setscrews being thereafter tightened to securely lock the barrel and sleeve together against further relative rotation. Axially concentric with the lock barrel 12 is a separate adjustable lock barrel 17 provided with external threads which mesh with the internal threads 8 of the sleeve, and journaled in the bore 7, in concentric relation with the lock barrels 12 and 17. 5 is a cylindrical end plug 18 having a peripheral groove 19 thereon in which the sleeve flange 11 seats so that the plug is prevented from movement out of the end of the sleeve. A pair of guide rods 21, having their opposite ends pressed into suitable sockets reamed into the barrel 12, and the plug 18 so as to fix the rods in place, pass freely through apertures therefor formed in the movable lock barrel 17 so that the latter may slide on the guide rods in the space between the confronting ends of the lock barrel 12 and the plug 18. It will be seen that if the setscrews 16 are loosened and the sleeve 4 is revolved relative to the lock barrel 12, movement of the screw threads 8 will cause the movable lock barrel 17 to be shifted axially in a selected direction toward either the lock barrel 12 or the plug 18.

Extending axially through the lock barrel 12, and positioned eccentrically with respect to the axis thereof, is a bore 22 in which is journaled one section 23 of a cylindrical lock rotor, having at one end a flange 24, which rests in a counterbore 26 formed in the face of the lock barrel 12 so as to prevent relative axial movement between the lock barrel and rotor in one direction, and provided with a longitudinally extending slot 27, of complex cross-sectional configuration into which the shank of a key 28 of complementary cross-sectional shape may be inserted.

A bore 29, axially aline with the bore 22, is provided in the movable lock barrel 17 in which is journaled a second separate section 31 of the lock rotor which is provided at each end with radially extending flanges 32 seated in counterbores 33 so that the rotor section 31 is secured in the movable lock barrel against axial movement relative thereto but is movable, as the lock barrel is moved toward either the lock barrel 12 or the plug 18. The rotor section 31 is provided with a slot 34 through which the shank of the key 28 may slidably pass. The plug 18 is provided with an eccentrically positioned bore 36, axially alined with the bores 22 and 29 of the lock barrels 12 and 17, in which is journaled a third section 37 of the lock rotor which also has extending axially therethrough a slot 38 for the reception of the key 28. A pair of radially spaced rods 39, best shown in Figure 3, are secured at their ends in the sections 23 and 37 of the rotor and pass freely through suitable apertures provided therefor in the rotor section 31. These rods tie all of the rotor sections for rotation together as a unit. A lever 41 secured to the end of the rotor section 37 by screws 42 is provided for engagement with the retractile bolt of the lock in any desired manner so that when the lock rotor is revolved by the key 28, the lock bolt may be moved to retracted or extended positions as desired.

The lock barrel 12 is provided with a plurality, preferably four, of transversely extending, 70 axially spaced, cylindrical tumbler bores 43 which are axially alined with similar bores 44 formed in the rotor section 23, and the movable lock barrel 17 and its rotor section 31 are also provided with like axially alined tumbler bores 75

46 and 47. The upper edge of the key shank is provided with the usual tumbler notches 48 which are cut to various depths and which receive the rounded lower ends of the lower tumbler sections 49. These tumbler sections are of such length that, when the key is in position in the slot provided therefor in the rotor, the upper end of each, as is shown in Figure 3, is positioned so that the rotor is free to be rotated in its bore. Also slidably mounted in each tumbler bore, above the lower tumbler section therein, is an upper tumbler section 51, and each bore contains a coil spring 52 which engages the end of each upper tumbler section so as to resiliently urge the latter downwardly into intimate contact with the lower tumbler section. Both of the lock barrels 12 and 17 are provided with dovetailed slots 53 in which are inserted plates 54 which engage the upper ends of the springs 52 so as to retain the latter in the tumbler bores. When the key 28 is withdrawn from the lock rotor the springs 52 will urge each tumbler downwardly in its bore so as to project the upper section 51 of each tumbler into the mating bores of the 20 rotor whereupon the rotor and lock barrels will be pinned together against relative rotation.

It will be seen that all of the structure contained in the lock barrel 12 is of conventional and well-known construction and that the only way the combination of the lock may be changed, as regards the first four tumblers reading from right to left in Figure 1, is by making the corresponding key notches 48 shallower or deeper with a corresponding lengthening or shortening of the lower tumbler sections 49. This obviously requires that the entire lock be dismantled so that the tumbler sections 49 may be removed. In the lock of my invention however this dismantling is not necessary since all that is required is the making of a new key 28 in which the spacing between the end notch, at the extreme end of the key as viewed in Figure 1, and its neighbor immediately to the right are changed from the original key. The new key is then inserted fully in the lock rotor, the setscrews 16 are loosened, the sleeve 4 is manually rotated so as to shift the movable lock barrels 17 axially so as to aline the tumbler with the newly cut key notch, which condition will become evident when the key may be rotated, and then tightening the setscrews 16 to secure the sleeve in its new position. While it is preferable that the newly cut key notch be the same depth as the corresponding notch of the old key, so that the tumbler will release when it is alined with the notch, it is not absolutely essential that this dimension be micrometrically duplicated since, if the notch is slightly deeper than the old one, the end of the tumbler, when the sleeve 4 has been rotated sufficiently to permit free rotation of the lock rotor by the key, will rest against a sloping side of the notch rather than the bottom thereof thus positioning the plane of division of the tumbler correctly with respect to the periphery of the rotor. The amount of axial adjustment of the movable lock barrel should not be less than $\frac{1}{6}$ of an inch so that at least as many combination changes may be obtained as is possible with the use of a key notch of the same depth.

The most important advantage gained by use of the lock of my invention is that combination changes may be effected without completely dismantling the lock, which obviously results in a considerable saving of time and effort. It will

be seen that it is not wholly impossible for a person who ordinarily knows nothing of lock construction, with the aid of simple and easily followed directions, to easily fit a new key to and change the combination of the lock of my invention. While I have shown and described a single movable lock barrel at the rear of the lock structure, it is obvious that the movable lock barrel may be duplicated at the forward end of the lock so that the range of combination changes may be greatly multiplied.

Having thus described my invention in detail, what I claim as new and desire to secure by Letters Patent is:

1. A lock comprising a tubular sleeve provided with an internal screw thread, axially aligned separate lock barrels and a plug positioned in and rotatable relative to said sleeve, a first of said lock barrels having a peripheral screw thread meshing with said internal screw thread of the sleeve, a pair of spaced guide rods secured at their ends in said plug and a second of said lock barrels, said first of the lock barrels being in slidable engagement with said guide rods, set-screws in said sleeve and engaging said second of the lock barrels for securing the latter and the sleeve against relative rotation, a rotor comprising separate cylindrical sections journaled respectively in said first and second lock barrels and in said plug, a pair of spaced second guide rods secured at their ends in the rotor sections of said plug and second lock barrel and being in slidable engagement with said first of the lock barrels, tumblers normally locking said rotor and lock barrels together against relative rotation, said rotor sections having aligned key way openings, and said tumblers normally projecting into said openings.

2. In a lock, a sleeve, a pair of axially aligned lock barrels rotatably mounted in said sleeve, said barrels having aligned bores whose axes are

parallel with the barrel axis, lock rotors arranged within said bores, said rotors and barrels having transversely disposed openings aligned with each other, tumblers in said openings, one of said barrels being threadedly engaged with the interior of said sleeve, means for holding said rotors against relative rotation, said rotors having axially aligned key openings, and the tumblers of said rotors normally projecting into said key openings.

3. In a lock, a fixed sleeve, a pair of axially aligned lock barrels rotatably mounted in said sleeve, one of said barrels being in threaded engagement with said sleeve, said barrels having aligned bores whose axes are parallel with the barrel axis, lock rotors arranged within said bores, said rotors and barrels having transversely disposed openings aligned with each other, a pair of tumblers arranged within each of said openings, a bar slidably connecting said lock barrels, said rotors having axially aligned key openings, the tumblers of said rotors normally projecting into said key openings, the second of said barrels being rotatable within said sleeve, and means for holding said barrel against rotation.

4. In a lock, a fixed sleeve, a pair of axially aligned lock barrels mounted within said sleeve, one of said barrels being movable toward or away from the other barrel, said barrels having aligned bores whose axes are parallel with the barrel axis, lock rotors arranged within said bores, said rotors and barrels having transversely disposed openings aligned with each other, a pair of tumblers in each of said aligned openings, means for holding said barrels against relative rotation, said rotors having axially aligned key openings, the tumblers of said rotors normally projecting into said key openings, and means for holding the second of said rotors in fixed engagement with said sleeve.

JOHN F. CHING.
